UNITED STATES PATENT OFFICE.

JOSEPH W. SKINNER, OF LA CROSSE, WISCONSIN.

DESIGN FOR A SHOE-SHAPER PLATE.

SPECIFICATION forming part of Design No. 21,694, dated July 5, 1892.

Application filed May 5, 1891. Serial No. 391,693. Term of patent 7 years.

To all whom it may concern:

Be it known that I, JOSEPH W. SKINNER, a citizen of the United States, residing at La Crosse, in the county of La Crosse and State 5 of Wisconsin, have invented and produced a new and original Design for Shoe-Shaper Plates, of which the following is a specification, reference being had to the accompanying drawing, in which the figure is a perspective view of a shoe shaper plate, showing my 10 design.

The edge lines of the flat main plate converge from a point *a* toward both ends. At

the ends of the plate are produced upwardly-projected shapes *B* and *C*, the shape *C* being 15 straight and at right angles to the surface of plate *A* and the shape *B* being projected forward slightly over the plate *A*, as shown.

I claim—

The design for a shoe-shaper plate, as shown 20 and described.

JOSEPH W. SKINNER.
